UNITED STATES PATENT OFFICE.

CHARLES GUERITEY, OF BROOKLYN, NEW YORK.

SELF-OPENING CONTAINER.

1,341,505.

Specification of Letters Patent. Patented May 25, 1920.

Application filed May 8, 1919. Serial No. 295,528.

To all whom it may concern:

Be it known that I, CHARLES GUERITEY, a citizen of the United States, and a resident of the city of New York, borough of Brooklyn, in the county of Kings and State of New York, have invented a new and Improved Self-Opening Container, of which the following is a full, clear, and exact description.

10 This invention relates to a new and improved container and more particularly to a container which is airtight and adapted to be self-opening.

One of the objects of this invention is to 15 provide a container having a cover and a main body portion, which is simple in construction, economical to manufacture and which may be opened without requiring the use of instruments or other means for separating the body from the cover therefor.

More specifically one of the objects of this 20 invention is to provide in an airtight box having a body and a cover therefor, said box being particularly adapted to receive 25 paste or other semi-liquid material, a means whereby the body and cover therefor may be separated by merely dropping the box suddenly.

A further object is to provide in a container, having a cover and a body portion, 30 a self-opening means which functions to separate the cover from the main body portion and serves as a holder or receptacle for the main body portion of the box both when 35 the cover is in position thereon and when removed therefrom so that the bottom of the main body portion of the box will at all times be spaced from the under surface upon which the receptacle rests, thus permitting 40 the free circulation of air around said box.

Still a further object of this invention is to provide in a container, having a body and cover therefor, a means for conveniently 45 separating the two parts by the sudden jarring of said means and which will act as a positioning member for the body of the box or container, so that to again apply the cover to the box, the cover is positioned 50 on said means above the box so that the cover and body portion of the box may be conveniently pressed between the fingers.

The above objects are substantially accomplished by providing a member so constructed and arranged as to normally hold 55 the box or container in spaced relation to

the surface upon which the member rests, so that if the said member is raised and suddenly dropped on the supporting surface, the cover and body portion of the box 60 will be separated.

Other objects and advantages will be apparent from the following specification and the accompanying drawings showing one of the preferred forms of this invention.

It is to be understood, however, that this invention is not limited to the exact construction here shown, but to cover broadly the feature of providing a member normally positioning the spacing box in spaced relation to a supporting surface so that if the spacing member is moved and suddenly stopped, the inertia of the body portion of the box will tend to cause the body of the box to continue to move through the distance which separates it from the supporting surface while the cover of the box is held in a fixed position, thus causing the body and cover to be separated.

Figure 1 is a vertical sectional view showing the box in a closed position with the edges of the cover resting upon the spacing member.

Fig. 2 is a vertical sectional view showing the position of the parts after the body 85 portion of the container has moved downwardly from the cover. This view also shows the relative position of the parts prior to the closing of the box, it being merely necessary to place the container between the fingers and pressing the same.

In the drawings showing one of the preferred forms of the invention, the cover 1 is provided with downwardly extending side portions 2, there being provided at the lower 95 edge thereof a bent or turned positioning edge 3.

The main body portion 4 of the box or container is formed with upwardly extending sides 5 and is provided with an inwardly 100 turned upper edge 6, which is formed to contact with the outwardly extending lower edge 3 of the cover to facilitate the application of the cover thereto. The body portion of the box is further provided with an 105 outwardly extending bead 7 between its upper and lower edges.

As a means of normally positioning the container in spaced relation to a supporting surface, a spacing member 8 is provided 110 which, in the preferred form, is shown as comprising a cylindrical casing having in

its upper end an inwardly turned bead 9, which is positioned between the outwardly turned edge 3 of the cover and the bead 7 formed in the body of the box. At the 5 lower edge of the spacing member 8 there is another bead 10 formed inwardly and of a larger diameter than the upper bead 9, it being of sufficient size to prevent the body 4 of the container from coming in contact 10 with the supporting surface when the cover is removed therefrom as shown in Fig. 2. The body of the box is held in the position as shown in Fig. 1 by frictional engagement with the cover 1 and the bead 7 of the 15 body of the box engaging the inwardly turned bead 9 of the spacing member prevents the further insertion of the body of the box within the cover. The distance between the top edge 6 of the box and the bead 20 7 should be such that when the body of the box is resting upon the lower bead 10 of the spacing member, the inwardly turned upper edge of the body of the box will project above the bead 9 of the spacing member 25 so that the lower outwardly turned edge 3 of the cover may be readily guided thereby to facilitate the application of the cover to the box.

It is understood that this box or container 30 is preferably made of stamped metal but any suitable material may be employed. A box, such as that herein shown, is particularly adapted to receive shoe paste, it eliminating the necessity of getting the fingers soiled in 35 removing the cover.

From the above description and the accompanying drawings, it is seen that in order to separate the two parts of the container or box, it is merely necessary to apply 40 a force suddenly to the spacing member 8. This is most readily done by grasping the member 8 and bringing it down suddenly upon the supporting surface. When this is done, the effect is to suddenly stop the 45 movement of the spacing member 8 and cover 1 so that the inertia of the body portion of the container will be sufficient to cause it to overcome the frictional engagement with the sides 2 of the cover 1 and 50 cause it to move downwardly, thus causing the cover and body of the box to be separated.

In the preferred form the body portion of the box is carried on the inwardly turned 55 bead 10. When the cover is separated from the body of the box, that part of the body above the bead 7 is guided by the inwardly turned bead 9. To apply the cover to the box, it is merely necessary to position the 60 cover on the upper edge of the bead 9 and the box may be then conveniently placed between the thumb and fingers when by pressing the thumb and fingers together, the box may be closed.

65 While but one preferred form of con-

struction has herein been shown, it is understood that various changes and modifications may be made thereof without departing from the spirit and scope of this invention.

Having thus described the invention, what I claim as new is:

1. A self-opening container comprising a body portion, a cover frictionally engaging said body portion and a spacing member in contact with the cover holding the body in spaced relation to a supporting surface, so that relative movement of the body and cover is effected by suddenly striking the spacing member. 70

2. A self-opening box comprising a body having a bead, a cover frictionally engaging said body and having a turned edge, and a means normally holding the box in spaced relation to a supporting surface, so that by 80 suddenly dropping the box on a supporting surface, the cover will be disengaged from the body. 85

3. A self-opening container comprising a body, a top frictionally engaging said body and a means supporting the top and normally holding the entire body in spaced relation to a supporting surface, whereby the top may be separated from the body by 90 suddenly striking the said means. 95

4. A self-opening container comprising a body, a top frictionally engaging said body and a means in contact with the top and normally holding the box in spaced relation to a supporting surface, said means comprising 100 a spacing member having one end supporting the container through the cover and the other end thereof extending below the bottom of the body.

5. A self-opening container comprising a 105 body, a top frictionally engaging said body and a means in contact with the top and normally holding the box in spaced relation to a supporting surface, said means comprising a spacing member having one end supporting the container through the cover and the other end thereof extending below the bottom of the body, said spacing member being provided at the bottom end thereof with an inwardly projecting portion on which the 110 bottom of the container rests when it is disengaged from the cover. 115

6. A self-opening box comprising a body having an outwardly projecting bead, a top frictionally engaging said body and having 120 an outwardly turned edge, a means to support the box in spaced relation to a supporting surface so that the cover of the box may be separated therefrom by striking said means. 125

7. A self-opening box comprising a body, a cover frictionally engaging said body and a spacing member having one end thereof supporting the cover of said box, said spacing member extending below the bottom of 130

the body so that the cover may be removed from said box when a force is applied to said spacing member.

8. A self-opening box comprising a plurality of frictionally engaging members and a means engaging one of said members and holding the box in spaced relation from a supporting surface, so that said members may be disengaged by striking said means.

10 9. A self-opening box comprising a plurality of frictionally engaging members and a spacing member having one end thereof in engagement with one of said parts and the other end thereof extending below the bottom of the box and resting upon a supporting surface so that when the spacing member is suddenly set upon the supporting surface, the parts of the box will be separated.

15 10. A self-opening box comprising a body

portion having a bottom and upwardly extending side portions, the upper ends of said side portions being bent inwardly and an outwardly extending bead in said upwardly extending sides between the top and bottom thereof, a cover to frictionally engage the upwardly extending side portion of the body, said cover having an outwardly extending edge to be guided thereover and a spacing member comprising a cylindrical shell having at its upper edge an inwardly turned bead adapted to be positioned between the outwardly extending bead of the bottom and the outwardly extending edge of the top, said spacing member having at the lower end thereof another larger inwardly turned bead positioned below the bottom of the body.

CHARLES GUERITEY.
